UNITED STATES PATENT OFFICE.

HJALMAR SWANSON, OF CHICAGO, ILLINOIS, ASSIGNOR TO CUMMINS PERFORATOR COMPANY, OF CHICAGO, ILLINOIS, A CORPORATION OF ILLINOIS.

INKING MECHANISM.

Original application filed October 25, 1922, Serial No. 596,728. Divided and this application filed November 8, 1923, Serial No. 673,505. Renewed December 18, 1926.

The invention relates to an inking mechanism or device and among its many useful applications has particular utility in connection with a machine for endorsing or otherwise marking checks or the like. This application is a division of my application Serial No. 596,728, filed October 25, 1922, for check endorser machine. An examination of the latter mentioned application will aid in 10 a complete understanding of one useful application of the present invention.

My invention contemplates the provision of an improved inking device or mechanism and has for its objects: to provide an inking mechanism composed of few parts simply and compactly arranged whereby convenience and accuracy in the operation thereof is insured; to provide an inking mechanism which may be readily and conveniently assembled within or removed from a check endorsing machine or the like; to provide an inking mechanism so designed as to prevent the accumulation of a superfluous quantity of ink on the inking roller and in which the 20 continuous feed of the proper amount of ink to the inking roller is definitely effected.

In addition to the general objects recited above, the invention includes among its advantages, such other improvements and advantages in construction and operation as are found to obtain in the structures and devices hereinafter described or claimed.

In the accompanying drawings, forming a part of this specification, and showing, for 35 purposes of exemplification, a preferred form and manner in which the invention may be embodied and practiced, but without limiting the claimed invention specifically to such illustrative instance or instances:

40 Figure 1 is a plan view of a portion of a check endorsing machine or the like, having assembled therein an inking device or mechanism constituting the preferred embodiment of the invention.

45 Fig. 2 is a side elevation of the same.

Fig. 3 is a view similar to Fig. 2 looking from the opposite side of the machine.

Fig. 4 is a longitudinal vertical sectional view on line 4—4 of Fig. 1.

50 Fig. 5 is a side elevation of the ink spreader.

Referring to the drawings, 1 and 2 designate a pair of co-extending arms which are rigidly secured at their lower ends to the

frame of the check endorsing machine (not 55 shown) and having pivotally and adjustably mounted in the free ends thereof, by means of stud shafts 3, 3', a second pair of arms or bracket members 4 and 5. Mounted in suitable bosses 6 and 7 in the free ends of the 60 members 4 and 5 and extending inwardly therefrom are a pair of supporting trunnions 8, 8'. These trunnions through the intermediary of ball bearings (not shown) of which their ends are fashioned to constitute the 65 cones, support the opposite ends of the printing or type roller 10 and provide a substantially frictionless bearing construction for the said type roller. The roller 10 is further provided with a removable type plate 11 carrying the fixed type on its outer surface and having a substantially rectangular aperture 12 through which projects the changeable data, contained within the roller 10, to be 70 printed on the check, and which data is in alignment with said aperture when the plate 11 is positioned on the roller 10. The check endorsing machine of which the present improvements may constitute a part, is preferably 75 automatic in operation and is actuated by the check or other piece of paper to be marked by the impression roller 10, the said roller 10 being actuated by the insertion of the check to be marked or endorsed. The 80 particular mechanism cooperating with the inserted check and by which the intermittent rotation of the impression roller 10 is obtained, forms the subject matter of my above 85 mentioned co-pending application and as the same is set forth in detail therein, will 90 not be further described.

Formed integrally with the inner surfaces of the members or arms 4 and 5 and suitably positioned thereon, is a pair of oppositely disposed bosses 13 and 14 having journaled 95 thereon by means of stud shafts 15 and 16, a pivotally mounted supporting frame 17. The frame 17 is provided with a pair of upwardly extending arms 18 terminating in yokes 18^a forming bearings for the ends of the shaft 19 of the inking roller 20, the latter being removably secured as by pins 21 for free rotation within said yokes.

The roller 20 is provided with a removable circumferential layer of felt 20^a or any 100 preferred ink absorbing material. A rearwardly projecting tail portion 22 of the frame 17 terminates in a socketed boss 23

which constitutes a seat for the short plunger 24 bearing against the upper end of a coil spring 25. The latter is seated in a socket 26 in a rearwardly extending portion of the 5 frame. A set screw 27 is threaded into the boss 23 of the frame 17 and bears at its lower end against the upper surface of the plunger 24. It will be seen by the arrangement described that any desired adjustment of the 10 frame 17 may be effected to bring the inking roller 20 into the proper cooperating relation with the type roller 10.

An ink receptacle 28 is provided, having 15 depending arms 29 at either end which are journaled on the stud shafts 15 and 16. The ends of the ink receptacle 28 are slotted as at 30 to provide a removable journal support for the shaft 31 of an ink spreader designated as an entirety by 32. The spreader 32 20 comprises a plurality of radially extending ink distributing pins 33 which, when the spreader is rotated, are immersed in the ink contained in the receptacle 28, and the ink deposited thereon is carried to and deposited 25 by frictional contact on the roller 20 during operation of the machine. As best seen in Fig. 1, the radially extending pins 33 of the ink spreader bears a staggered or spiral relation to one another about the hub of the 30 shaft 31 with the result that the ink carried up from the receptacle 28 is widely distributed in small drops over the inking pad 20^a of the ink roller 20, and the ink so distributed is spread by capillary attraction over 35 the entire inking surface of such roller. This arrangement insures an even distribution of the ink over the surface 21 and prevents an oversupply of ink thereto.

The slotted construction 30 permits ready 40 and convenient removal of the ink spreader 32 from the ink receptacle when desired, and the ink roller 20 may be conveniently removed from the yoke portions 18^a of the arm 18 by removing the pins 21 from said 45 yokes.

The ink spreader 32 is held in constant engagement with the inking roll 20 by means 50 of a coil spring 34, seated in and engaging opposed sockets 35, 35^a in the ink receptacle 28 and the rearwardly extending tail portion 22 of the frame 17. This tension may be varied to any desired extent by adjusting a set screw 36 having a threaded engagement in a boss 37 provided at one end of the ink 55 receptacle 28 and bearing at its other end against the frame 17.

The operation of the mechanism above described is as follows:

A check 38 or other slip of paper to be 60 printed or endorsed is fed by suitable mechanism (not shown) into contact with the mechanism which actuates the intermittently rotating printing roller 10. The desired impression is made upon the check by the 65 rotation of the said printing roller 10 with

which said check is in contact and this rotation of the roller 10 is imparted to the inking roller 20 which in turn imparts said rotation to the ink spreader 32 by means of the radially extending pins 33 with which the 70 roller 20 is in contact. The various rotations described are maintained as long as the checks or other material to be marked are fed to the impression roller 10. After the type has made the desired impression on the 75 check, it passes around and revolves the inking roller 20 and receives therefrom a fresh supply of ink on its type surface, to be applied to the following check on the next 80 ensuing revolution of the type roller.

The intermittent rotation of the type roller 10 and ink roller 20 causes a similar intermittent rotation of the ink spreader 32 which feeds and widely distributes a fresh supply of ink to the inking roller, thus insuring at all times adequate and continued 85 ink supply to the type surfaces.

When desired, an ink spreader having a greater or lesser number of staggered, spirally arranged ink-distributing fingers may 90 be conveniently substituted in the mechanism described by reason of the slotted journal construction 30 of the ink receptacle 28.

The invention as hereinabove set forth may be variously embodied within the scope 95 of the claims hereinafter made.

What I claim is:—

1. An inking device for the purpose described, comprising in combination: an inking roller adjustably mounted with respect 100 to and adapted to be rotated by a printing device, an ink receptacle adjustably mounted with respect to said inking roller, an ink spreader having distributing devices spaced circumferentially and longitudinally thereon 105 and rotatably mounted in said receptacle, said ink spreader being adapted to be rotated by said inking roller to transfer the ink from the receptacle and to distribute it over the surface of said inking roller, whereby ink is deposited on said printing device during the rotation of said inking roller and said ink distributing spreader. 110

2. An inking device for the purpose described, comprising in combination: an inking roller adapted to be rotated by a printing 115 device, an ink receptacle, an ink spreader having distributing devices spaced circumferentially and longitudinally thereon 120 and rotatably mounted in said receptacle, said ink spreader being adapted to be rotated by said inking roller to transfer the ink from the receptacle and distribute it over the surface of said inking roller, whereby ink is deposited on said printing device during the rotation of said inking roller and said ink distributing spreader. 125

3. An inking device for the purpose described, comprising in combination: an ink roller engaging and adapted to be rotated 130

- by a printing device, said ink roller having a fibrous inking surface, an ink spreader engaging said roller, said ink spreader having distributing devices spaced circumferentially and longitudinally thereon to insure the distribution of ink at spaced intervals on the fibrous surface of said ink roller when the latter is rotated by said printing device.
- 10 4. An inking device for the purpose described, comprising in combination: an ink roller engaging and adapted to be rotated by a printing device, an ink receptacle, an ink spreader operatively mounted in said receptacle and constituted of ink distributing pins arranged in mutually staggered relation and engaging said ink roller to obtain a spaced distribution of ink to said ink roller.
- 15 5. An inking device for the purpose described, comprising in combination: an ink roller engaging and adapted to be rotated by a printing device, an ink receptacle, an ink spreader, operatively mounted in said receptacle and constituted of spirally arranged ink distributing pins engaging said ink roller to obtain a spaced distribution of ink on said ink roller.
- 20 6. An inking device for check-endorsing machines and the like, comprising in combination: an impression roller adapted to be intermittently rotated, an inking roller adjustably mounted and adapted to cooperate with said impression roller, an ink receptacle adjustably mounted with respect to said inking roller, an ink spreader rotatably and removably mounted in said receptacle, spaced ink-distributing fingers carried by said ink spreader and adapted to cooperate with said inking roller, whereby the intermittent rotation of said impression roller is transmitted to said ink spreader to distribute ink on said inking roller by said ink-distributing fingers.
- 25 7. An inking device for check-endorsing machines and the like, comprising in combination: an impression roller, an inking roller adapted to cooperate with said impression roller and be rotated thereby, an ink receptacle mounted adjacent said inking roller, an ink spreader rotatably mounted in said ink receptacle and adapted to cooperate with said inking roller, and a plurality of staggered ink-distributing fingers carried by said ink spreader to transfer ink from said ink receptacle and distribute it on said inking roller.
- 30 8. In an inking mechanism, in combination: a frame, an impression roller mounted within said frame, an inking roller adjustably mounted in said frame and adapted to cooperate with said impression roller, an ink receptacle adjustably mounted relative to said inking roller, an ink spreader rotatably and removably mounted in said receptacle, a plurality of ink-distributing pins mounted in staggered relation on said ink spreader and contacting with said inking roller, and means for adjusting said inking roller relative to said impression roller, whereby ink is removed by said spreader from said receptacle and deposited on said inking roller.
- 35 9. In an inking mechanism, in combination: a frame, an impression roller mounted within said frame, an inking roller adjustably mounted in said frame and adapted to cooperate with said impression roller, an ink receptacle adjustably mounted relative to said inking roller, an ink spreader rotatably and removably mounted in said receptacle, and a plurality of ink-distributing pins on said ink spreader and contacting with said inking roller.
- 40 10. In an inking mechanism, in combination: a frame, an impression roller mounted within said frame, an inking roller adjustably mounted in said frame and adapted to cooperate with said impression roller, an ink receptacle adjustably mounted relative to said inking roller, an ink spreader rotatably and removably mounted in said receptacle, and a plurality of ink-distributing pins mounted in staggered relation on said ink spreader and contacting with said inking roller.
- 45 In testimony whereof I have hereunto set my hand.

HJALMAR SWANSON.
